UNITED STATES PATENT OFFICE.

JOHN S. WORTH, OF COATESVILLE, PENNSYLVANIA, ASSIGNOR TO HIMSELF AND
WILLIAM P. WORTH, OF COATESVILLE, PENNSYLVANIA.

CAR CONSTRUCTION.

1,273,564.

Specification of Letters Patent. Patented July 23, 1918.

Application filed December 31, 1915. Serial No. 69,671.

To all whom it may concern:

Be it known that I, JOHN S. WORTH, a citizen of the United States, and a resident of Coatesville, county of Chester, State of Pennsylvania, have invented certain Improvements in Car Construction, of which the following is a specification.

One object of my invention is to construct a substantial metallic freight car of the box type from sheet metal pressed into shape to form plates, girders and posts so that the structure will resist the strains to which this type of car is subjected.

A further object of the invention is to provide means for securing the lining to the car body.

In the accompanying drawings:

Figure 1 is a side view of one-half of the car body, illustrating my invention;

Fig. 2 is an end view of the car body;

Fig. 3 is a sectional plan view of the car body on the line 3—3, Fig. 1;

Fig. 4 is a vertical sectional view on the line 5—5, Fig. 1;

Fig. 5 is an enlarged sectional view at the girder on the line 5—5, Fig. 1;

Fig. 6 is a perspective view, showing the horizontal joint girder;

Fig. 7 is a section on the line 7—7, Fig. 2;

Fig. 8 is a perspective view showing the rear of one of the sections of the lining;

Fig. 9 is a perspective view of one of the blocks to which the lining is secured; and

Figs. 10 and 11 are views illustrating a modification of the girder joint.

Referring to the drawings, 1 is the lower frame of the car. 2 is the cornice frame. 3 is the roof, which may be made in any suitable manner. 4, 4 are the vertical side posts. 5, 5 are the vertical end posts and 6, 6 are the vertical corner posts. 7, 7 are the side plates which extend from one post 4 to another and 8, 8 are the end plates which extend from one post to another. The side plates 4 are made, as clearly shown in Fig. 3, of plates bent up to form the body of the posts and to provide flanges 9 by which the posts are secured to the side plates. The side plates 7 are preferably corrugated to add strength to the structure and these corrugations, in the present instance, run diagonally with respect to the vertical posts and some of the plates are corrugated diagonally in one direction, while others are corrugated diagonally in the opposite direction, form-

ing integral struts which brace the car structure so as to dispense with the ordinary struts which are usually diagonally arranged between the posts. It will be understood, however, that the corrugations may be arranged in any manner desired without departing from the essential features of the invention. In the present instance, the plates 8 have a series of vertical corrugations and these may be arranged at an angle or in any manner desired.

There are preferably two plates 7 and 7^a between each side post, one plate being located above the other and at the horizontal joint between the two plates is a girder 10. In the present instance, this girder is pressed up from the upper plate 7^a and extends over the upper edge of the lower plate 7, as clearly shown in Fig. 6. The girder is tapered toward each end so that the entire plate can pass back of the flanges of the vertical posts and be secured thereto. The girders thus formed materially strengthen the car body. I find that a single girder in the majority of cars will give the strength desired at the side of the car, but I prefer to form two sets of girders, as at 11 and 12, at the ends of the car, making the end out of three vertically arranged plates instead of two, as at the sides, but, in some instances, where a car of great strength is desired there may be three, or even more than three, plates at the sides and transverse beams at the joints of the several plates.

The vertical edges of the side plates underlap the flanges of the posts, as shown in Fig. 3, and tie plates 13 extend back of the flanges and add strength to the post structure.

14 is the lining of the end of the car and 15 is the lining of the sides of the car. These linings may extend to any height desired. I locate comparatively short blocks 16 in the hollow transverse beams 10 and fasten the linings thereto by means of screws 17, or other fastening devices. In some instances, screws 18 may be used to attach the blocks to the metallic body structure, the screws passing through the rear plate, as clearly shown in Fig. 5. The same construction is preferably carried out in fastening the end linings 14 to the ends of the car.

The battens 25 of the sections of the linings 15 are preferably made of metal and are located in the corrugations of the side and

2
end plates and when the corrugations are arranged diagonally, as in Fig. 1, then the battens are also arranged diagonally, as in Fig. 8, so that they will extend into the corrugations, as it is desirable that the linings shall rest against the side plates and the end plates of the car body. The linings are preferably made in sections of a sufficient size so that the sections can be readily detached from the car body and removed therefrom and they may be arranged with the boards running vertically or horizontally, as desired.

In Figs. 10 and 11, I have illustrated a modification, in which the lower plate 7^b stops at the lower flange of the plate 7^a and one or more connecting strips 10^a may be used if desired, in place of the continuous plate, as in Fig. 6.

20 It will be understood that any number of rivets may be used to secure the plates to the posts so as to make a substantial structure.

I claim:

1. The combination in a car structure, of a base frame and a cornice frame; a series of vertical posts connected to the two frames; a series of plates mounted between the posts and secured thereto, the edges of one of the plates of each series being shaped to form a

hollow transverse girder, the girders being 30 reduced at each end so that the entire plate can be secured flat against the posts.

2. The combination in a car structure, of a base frame and a cornice frame; a series of vertical posts connected to the two frames; 35 a series of plates mounted between the posts and secured thereto, the lower edges of the upper plates lapping over the upper edges of the lower plates, said lower edge of the upper plate being shaped to form a hollow 40 transverse girder tapered at each end and secured to the lower plate and underlapping the vertical posts and secured thereto.

3. The combination in a car structure, of a base frame and a cornice frame; vertical 45 posts spaced apart at each side of the car and secured to the base frame and to the cornice frame; a series of vertical posts at the ends of the car arranged closer together than those at the sides and secured to the 50 base frame and to the cornice frame, and two series of corrugated plates, one series located above another, one plate of each series overlapping the other, the overlapping plates being shaped to form a hollow transverse 55 girder, the sides of the plates extending back of the posts and secured thereto.

JOHN S. WORTH.
